UNITED STATES PATENT OFFICE.

WILBER A. MCCOY, OF PITTSBURGH, PENNSYLVANIA.

ROLLER-SKATING TRACK.

1,325,026.

Specification of Letters Patent. Patented Dec. 16, 1919.

Application filed March 11, 1919. Serial No. 231,925.

To all whom it may concern:

Be it known that I, WILBER A. MCCOY, a citizen of the United States, residing at Pittsburgh, in the county of Allegheny and State of Pennsylvania, have invented certain new and useful Improvements in Roller-Skating Tracks, of which the following is a specification.

This invention relates to roller skating rinks and more particularly to the floors thereof, and the object of the invention is to provide a floor which is constructed to form an undulatory track or skating surface, whereby a simple means for a pleasurable and enjoyable method of roller skating, with the least possible exertion, is had.

In order that the invention may be better understood, reference is had to the accompanying drawing forming a part of this specification, and in said drawing,

Figure 1 is a plan view of a fragment of the track;

Fig. 2 is an elevation or edge view of the track, and

Figs. 3 and 4 are cross sections on the lines 3—3 and 4—4, respectively, of Fig. 2.

Referring specifically to the drawing, the track is made up of four parallel sections designated by the reference characters 5, 6, 7 and 8, respectively. The sections 5 and 6 are on the outside of the track, and the sections 7 and 8 are located alongside each other between said outer sections.

The outer sections 5 and 6 of the track have plane surfaces, and the inner track sections 7 and 8 each have an undulatory surface, the same being made up of a series of alternating inclined planes. The high points of the track section 7 are shown at *a* and the lower points at *b*, whereas the high and low points of the track section 8 are shown at *c* and *d*, respectively. It will be noted that the high points of one track section are in line with the low points of the other section, and hence the high points of the two sections follow each other in alternate order. This arrangement produces a series of ascending and descending surfaces, the descending surface of one track section being alongside the ascending surface of the other section. The ascending surfaces of the section 7 are shown at *e* and the descending surfaces at *f*, whereas the ascending and descending surfaces of the section 8 are shown at *g* and *h*, respectively.

The drawing shows the track arranged in

a straight line, but it can be built in a curve, or in the form of a circle or in any other desired shape, and it is intended principally as an addition to roller skating rinks, parks or amusement places of any kind, but it can also be used for travel from place to place where desired to lay such a track for convenience of pedestrians who would use roller skates instead of walking.

In using the track, motion is acquired by the skater merely shifting the weight of his body from one foot to the other. The action is as follows, it being assumed that the skater is going in the direction of the arrow, and that one foot is on the track section 6 and the other foot on the section 8:

The skater, starting at the high point *c* on track section 8, coasts down the incline *h* on his right foot to the low point *d*, the skate on the left foot being on the floor section 6. At the low point *d*, the skater shifts his weight to the left foot and skates on the level track section 6 until the right foot reaches the next high point on the section 8, where he again shifts his weight to his right foot and coasts down the next incline *h*, and so keeps in motion by successively shifting his weight from one foot to the other at the high and low points of the track sections 8.

The track sections 5 and 7 will be used in the same manner as the sections 6 and 8, the skaters however traveling in opposite directions.

When the skater wishes to travel faster than the speed that can be obtained by using the track sections 6 and 8 (or 5 and 7), he can use the sections 7 and 8. He then starts at the high point *c* of section 8 and coasts down the incline *h* to the low point *d* on his left foot, and then when he reaches the point *d* he shifts his weight to the right foot and coasts on this foot down the incline *f* of the section 7, and when he reaches the bottom of the incline he shifts his weight to his left foot to coast down the next incline of the section 8, and so on in a continuous horizontal wave-like motion with practically no exertion whatsoever.

When the floor is made in a straight line, the sections 6 and 8 can be used to skate in one direction, and the sections 5 and 7 to return; or any number of track sections can be arranged alongside each other.

The tracks can be built into one unitary structure to rest on the ground or on a floor, and they can also be built to form the floor

of a skating rink structure. The height of the inclines will be such that there will be no danger of the skaters falling off and getting injured.

5 I claim:

1. A track for roller skating comprising a plane section, and another section alongside the same having an undulatory surface, the undulations running in the direction of the length of the plane section and their surface in a direction transverse of the latter being plane.
- 10 2. A track for roller skating comprising a plane section, and another section alongside the same composed of a series of successive descending and ascending inclines, said inclines running in the direction of the length of the plane section and their surface in a direction transverse of the latter being plane.
- 15 3. A track for roller skating comprising

two sections arranged alongside each other, and each composed of successive descending and ascending inclines, the descending inclines of one section being opposite the ascending inclines of the other sections, and vice versa.

4. A track for roller skating comprising two sections arranged alongside each other, and each having an undulatory surface, and plane track sections on one side of each of the aforesaid sections.

5. A track for roller skating comprising two sections arranged alongside each other, and each composed of successive descending and ascending inclines, the descending inclines of one section being opposite the ascending inclines of the other sections, and vice versa, and plane track sections on one side of each of the aforesaid sections.

In testimony whereof I affix my signature.

WILBER A. McCOY.
